UNITED STATES PATENT OFFICE.

CORINNA THACHER ROGERS, OF ANSONIA, CONNECTICUT.

DESIGN FOR A PIN-TRAY.

SPECIFICATION forming part of Design No. 26,217, dated October 27, 1896.

Application filed July 11, 1896. Serial No. 598,904. Term of patent 31 years.

To all whom it may concern:

Be it known that I, CORINNA THACHER ROGERS, a citizen of the United States, and a resident of Ansonia, in the county of New Haven and State of Connecticut, have invented a certain new and original Design for Pin-Trays, of which the following is a specification.

Upon the accompanying drawings, which form a part of this specification, Figure 1 shows a plan view of my novel design, and Fig. 2 a cross-section of the same on line *xx* of Fig. 1.

Said drawings, as will be seen, are a substantial representation of a sea-shell.

The leading or characteristic features of my design consist in the shape, configuration, and ornamentation, as shown, of a shallow sea-shell *A* of the scallop species, having a coast - scene decoration. Said shell is provided with an irregular - shaped edge, as shown, and a bow of ribbon *B* attached to the upper end in a neat and attractive manner.

In plan view the body of my design is practically round and has attached to its upper ²⁵ end a bow of ribbon.

The top end of the design is straight, as at *C*, for a short distance, whereupon it is drawn in and carried around in substantially a circle. Said edge is further ornamented by irregular-sized scallops *D*, which, in part, are preferably ornamented by being bronzed. The shallow interior of the shell is decorated with a coast scene, illustrating a sea-shore and a windmill.

Having thus described my invention, I claim—

The design for a pin-tray or similar article, substantially as shown and described.

Signed at Bridgeport, in the county of Fairfield and State of Connecticut, this 8th day of July, A. D. 1896.

CORINNA THACHER ROGERS.
